[57] CLAIM

The ornamental design for an envelope with decorative openings, as shown.

DESCRIPTION

FIG. 1 is a perspective view of an envelope with decorative openings in accordance with my new design;

FIG. 2 is a front elevational view of the envelope with decorative openings of FIG. 1;

FIG. 3 is a rear elevational view of the envelope with decorative openings of FIG. 1 with the flap in a closed position;

FIG. 4 is a rear elevational view of the envelope with decorative openings of FIG. 1 with the flap in the open position;

FIG. 5 is a top plan view of the envelope with decorative openings of FIG. 1 with the flap in the closed position, the bottom plan view being a mirror image thereof; and,

FIG. 6 is a left side elevational view of the envelope with decorative openings of FIG. 1 with the flap in the closed position, the right side elevational view being a mirror image thereof.
